LLP(57) **CLAIM**

The ornamental design for a lamp with socket, as shown and described.

DESCRIPTION

FIG. 1 is a front view of lamp with socket illustrating my new design;

FIG. 2 is a top view thereof;

FIG. 3 is a bottom view thereof;

FIG. 4 is a rear view thereof;

FIG. 5 is a left side view thereof;

FIG. 6 is a right side view thereof; and,

FIG. 7 is a front perspective view thereof.

The broken line showing represents portions of the article not claimed and forms no part of the claimed design.

The lamp with socket may be used in electric cabinets.
